UNITED STATES PATENT OFFICE.

HARRIS HANFLIG, OF CHARLESTOWN, MASSACHUSETTS.

PADLOCK.

1,058,861.

Specification of Letters Patent. Patented Apr. 15, 1913.

Application filed May 14, 1912. Serial No. 697,260.

To all whom it may concern:

Be it known that I, HARRIS HANFLIG, a citizen of the United States, residing at Charlestown, in the county of Suffolk and State of Massachusetts, have invented a new and useful Improvement in Padlocks, of which the following is a specification.

This invention relates to a combination pad lock, and more specifically to certain improvements upon the lock for which a patent was granted to me August 8, 1911, Number 999,990.

The objects of these improvements is to simplify the construction of the lock itself, the manner of securing the back in place and to reduce the cost of construction without affecting the durability of the lock.

With these objects in view, the invention consists of the novel features of construction hereinafter fully described, pointed out in the claims, and shown in the accompanying drawings, in which,

Figure 1 is a face view. Fig. 2 is a vertical section. Fig. 3 is a section on the line 3—3 of Fig. 2. Fig. 4 is a section on the line 4—4 of Fig. 2. Fig. 5 is a perspective view of one of the rings. Fig. 6 is a detail sectional view showing in plane portions of the inner faces of flanges carried by certain rings.

In these drawings, 1 represents a cylindrical casing which at its front is provided with a rabbeted flange 2, within which rotates a dial plate 3, provided with a suitable notch 35 or mark 4 and the outer face of the flange 2 is provided with a suitable scale 5. The dial plate is provided with a milled head 6 by means of which it can be readily turned. A back plate 7 fits over the rear end of the casing 1 and is provided with an annular flange 8, which fits within the casing 1 and bears against the inner face of the flange 2. A shackle 9, the free end portion of which is provided with oblique grooves 10, upon 45 its opposite sides, is constructed and mounted the same as the shackle shown in my previous patent. This shackle is adapted to be lifted vertically a certain distance, then to be swung to one side. The flange 8 is slotted as shown at 11 to permit said shackle to pass therethrough, the casing 1 of course having a suitable slot 1^a for this purpose. The back plate is locked in position by means of a bayonet slot 12, cut in the flange 8, 55 which slot engages a pin 13, carried by the casing 1. This greatly simplifies the secur-

ing of the back plate in position over the construction shown in my previous patent.

Placed within the casing are two rings 14 and 14^a, said rings being recessed or cut-away as shown at 15, and when said rings are turned in order to bring said recesses into alinement with each other a circular opening is formed through which the free end of the shackle can pass, provided of course the rings are also turned into such position that the opening so formed by the recess 15 will register with the openings 1^a and 11.

When the end of the shackle is passed through said openings, the rings can then be turned so as to cause them to travel in the grooves 10, respectively, thus locking the shackle within the casing. Each ring is provided with an interior flange 16, and on said flanges are formed suitable teeth 17, the depth of said teeth being less than that of the flanges. Fitting within the rings and resting upon said flanges and meshing with the teeth 17 are toothed wheels 18 and 19, 80 and said wheels carry pins 20 and 21, so situated that upon rotation of said wheels one pin will engage the other.

The wheel 18 is secured in place by a suitable screw 22 and the wheel 19 receives a 85 suitable stub shaft 24 formed on the back plate 7 and provided with a threaded portion upon which is fixed a suitable nut 23.

It will be obvious that by turning the dial 3, the wheel 18 will be turned and this in 90 turn will rotate the ring 14. When the pin 20 picks up the pin 21, the wheel 19 and the ring 14^a will be turned, the back plate however remaining stationary as the wheel 19 turns loosely upon the stub shaft 24 carried by said back plate.

The wheels 18 and 19 are readily detachable from their respective rings, and by detaching them or any one of them and reinserting the same within the ring with the 100 pin or pins occupying a different relative position with respect to each other changes can be made in the combination.

What I claim is:

1. A lock of the kind described comprising a casing having an interior flange adjacent its front, said flange being rabbeted, a dial plate turning within said flange and bearing thereupon, a back plate adapted to close the inner end of the casing and having 110 an annular flange adapted to fit within the casing and to bear against the first men-

tioned flange, a stub shaft carried by said back plate, a toothed wheel turning loosely upon said stub shaft, a flanged ring mounted upon said toothed wheel and turning therewith, said ring being notched, a similar wheel fixed upon the inner face of the dial plate, a flanged and notched ring mounted on and turning with said last mentioned wheel, pins carried by said wheels and adapted to engage each other, a shackle adapted to pass through the opening formed by the registering of the ring notches, said shackle being grooved upon opposite sides to receive the rings, and means for locking said back plate in position, said plate being removable when the shackle is withdrawn from the lock.

2. A device of the kind described comprising a cylindrical casing, a back plate therefor, a flange carried by the back plate, and adapted to fit within the casing, said flange and casing having openings adapted to register, a pin carried by the casing, said flange having a bayonet slot in which said pin rests when the opening of the flange registers with that of the casing, a shackle adapted to pass through said openings and means arranged within said flange for locking said shackle against withdrawal.

HARRIS HANFLIG.

Correction in Letters Patent No. 1,058,861.

It is hereby certified that in Letters Patent No. 1,058,861, granted April 15, 1913, upon the application of Harris Hanflig, of Charlestown, Massachusetts, for an improvement in "Padlocks," an error appears in the printed specification requiring correction as follows: Page 2, line 28, for the numeral "4" read *for*; and that the said Letters Patent should be read with this correction therein that the same may conform to the record of the case in the Patent Office.

Signed and sealed this 6th day of May, A. D., 1913.

C. C. BILLINGS,

Acting Commissioner of Patents.

tioned flange, a stub shaft carried by said back plate, a toothed wheel turning loosely upon said stub shaft, a flanged ring mounted upon said toothed wheel and turning therewith, said ring being notched, a similar wheel fixed upon the inner face of the dial plate, a flanged and notched ring mounted on and turning with said last mentioned wheel, pins carried by said wheels and adapted to engage each other, a shackle adapted to pass through the opening formed by the registering of the ring notches, said shackle being grooved upon opposite sides to receive the rings, and means for locking said back plate in position, said plate being removable when the shackle is withdrawn from the lock.

2. A device of the kind described comprising a cylindrical casing, a back plate therefor, a flange carried by the back plate, and adapted to fit within the casing, said flange and casing having openings adapted to register, a pin carried by the casing, said flange having a bayonet slot in which said pin rests when the opening of the flange registers with that of the casing, a shackle adapted to pass through said openings and means arranged within said flange for locking said shackle against withdrawal.
